(57) **CLAIM**

We claim the ornamental design for an evaporator cover, as shown and described.

DESCRIPTION

FIG. 1 is a perspective view of an evaporator cover embodying the present invention.

FIG. 2 is a bottom view of the evaporator cover shown in FIG. 1.

FIG. 3 is a top view of the evaporator cover shown in FIG. 1. FIG. 4 is a front view of the evaporator cover shown in FIG. 1.

FIG. 5 is a rear view of the evaporator cover shown in FIG. 1; and,

FIG. 6 is a right side view of the evaporator cover shown in FIG. 1, the left side view being a mirror image thereof.

The present application is directed to the shape and contour of an evaporator cover of the design illustrated in the drawings.
